UNITED STATES PATENT OFFICE.

CHARLES WILLIAM HIGGS, OF LONDON, ENGLAND.

INTERNAL-COMBUSTION ENGINE.

957,336.

Specification of Letters Patent. Patented May 10, 1910.

Application filed August 28, 1909. Serial No. 515,085.

To all whom it may concern:

Be it known that I, CHARLES WILLIAM Higgs, a subject of the King of Great Britain and Ireland, residing at 4 Fulford Mansions, Fairmead Road, Tufnell Park, London, England, have invented certain new and useful Improvements in Internal-Combustion Engines, of which the following is a specification.

10 This invention relates to improvements in internal combustion engines of the type in which two pistons are employed working one within the other in contrary directions.

I propose to place between the outer and 15 inner pistons a subsidiary intermediate cylinder which separates them and to utilize this cylinder for cooling purposes. The cylinder is in the form of a water jacket through which cooling water circulates and the interior of the engine is thus cooled in a more 20 direct manner than is possible with the ordinary external jacket alone. The two pistons are also kept apart, though working one within the other, and travel in what are 25 really separate intercommunicating cylinders.

In order that my invention may be more readily understood, reference is had to the accompanying sheet of drawings in which:— 30 Figure 1 is a longitudinal section of my improved engine; and Fig. 2 is a transverse section of the inner cylinder on the broken line $x-y$ of Fig. 1.

The outer cylinder A is as usual provided 35 with a cooling jacket a and has an admission opening a^1 in the top. The cylinder is mounted upon the engine casing B which serves to support, through the internal flange b , the subsidiary or inner cylinder C, 40 in the form of an internal water jacket, having the cooling water inlet and outlet c and c^1 , shown in Fig. 2. The lower end of this cylinder forms an exhaust space or ring D with ports d and exhaust pipe d^1 .

45 The upper or outer piston E travels within the cylinder A and encircles the subsidiary cylinder or water jacket C, on which it slides. It is connected through rods e at each side (passing through openings in flange b) to the cranks f of the engine shaft F. Within the cylinder C is the second or inner piston G traveling in the opposite direction to E and connected by the central piston rod g to the crank f^1 set oppositely to the cranks f . The central crank f^1 is of 50 greater length than the outer cranks f to

give the inner piston an increased stroke. This compensates for its smaller area and distributes the power more equally between the pistons. The volume swept by the piston E in the cylinder A should be equal to the volumes swept by the separation of the two pistons. It will be noted that the connecting rods do not differ greatly in length owing to the relative positions of the pistons and the compact construction. 60

The ignition plug is placed at h in the lower end of the cylinder A and at the side of the ignition space or chamber H formed between the two pistons. Communication is established at the proper moment between this ignition and working space H and the outer end of the cylinder A by means of the channels or ring of recesses a^2 and the corresponding ports e^1 in the piston 70 E, which uncover the recesses a^2 at the end of the outer stroke. Valves may be used in place of this arrangement if found preferable. The water jacket or inner cylinder C partly divides the ignition space H by 75 the overhanging portion c^2 thus increasing the cooling surface and assisting the scavenging, insuring the new charge being separated from any remaining products of combustion and eliminating the probability of missfires. 80

The general operation is as follows: As the pistons approach each other the charge is drawn into the outer cylinder A through the induction valve, while the charge previously admitted through the ports e^1 and 90 channels a^2 to the interior of the piston E is compressed between the two pistons, which by their different throw perform equal work in compressing. At about the position of greatest compression, as shown in Fig. 1, the charge in the explosion space H is fired by the ignition plug and the pistons E and G separate throughout the working stroke. Toward the end of this outer stroke the piston G uncovers the exhaust ports d 95 through the cylinder C; thereupon the ports e^1 of the piston E are opened to the channels a^2 and the charge which has in the meantime been compressed in the upper end of the cylinder A expands into the internal 100 chamber between the pistons and drives out the products of combustion before it. The top e^2 of the piston E is downwardly conical in shape to assist scavenging and has radial strengthening ribs e^3 on its upper side which 105 assist in cooling the top of piston. The top of the inner piston is also conical upwardly. 110

As the charge rushes in on all sides through the channels α^2 it is directed toward the center and is not scattered throughout the space. The conical tops of the pistons assist in guiding the charge and the escaping products in the proper direction so that the used up gases are driven outwardly into the exhaust ring at the bottom. Soon after the beginning of the return stroke both the exhaust and inlet ports are closed and the compression begins, repeating the cycle of operations above described.

What I claim as my invention and desire to secure by Letters Patent is:—

- 15 1. In an internal combustion engine, the combination with an outer cylinder and two oppositely moving pistons traveling one within the other, of a secondary intermediate cylinder separating the two pistons.
- 20 2. In an internal combustion engine, the combination with an outer cylinder and two oppositely moving pistons traveling one within the other, of a secondary intermediate cylinder in the form of a water jacket separating the two pistons and giving an internal cooling surface.
- 25 3. In an internal combustion engine the combination with an outer cylinder and two

oppositely moving pistons, of a separating cylindrical water jacket between the pistons, 30 having an overhanging flange at its inner end.

4. In an internal combustion engine having two oppositely moving telescopic pistons, a secondary separating cylinder between the pistons in the form of a water jacket, having exhaust ports at its outer end 35 uncovered by the inner piston.

5. In an internal combustion engine, the combination with an external cylinder having a compression space at its outer end and admission channels immediately below the compression space, an outer piston having admission ports around its sides admitting the explosive mixture to its interior and an 40 internally coned end, an inner piston with coned end and a secondary separating cylinder between the two pistons having exhaust ports uncovered by the inner piston, 45 substantially as herein described.

In witness whereof I have hereunto set my hand in the presence of two witnesses.

CHARLES WILLIAM HIGGS.
